US0D1077027S

(12) **United States Design Patent** (10) **Patent No.:** **US D1,077,027 S**
(45) **Date of Patent:** **** May 27, 2025**

(54) **CAMERA**

(71) Applicant: **GoPro, Inc.**, San Mateo, CA (US)

(72) Inventors: **John George Muhlenkamp, IV**,
Mapleton, UT (US); **Huy Phuong
Nguyen**, Alpine, UT (US)

(73) Assignee: **GoPro, Inc.**, San Mateo, CA (US)

(***) Term: **15 Years**

(21) Appl. No.: **29/947,848**

(22) Filed: **Jun. 18, 2024**

Related U.S. Application Data

(63) Continuation of application No. 29/756,987, filed on Nov. 2, 2020, now Pat. No. Des. 1,038,209, which is a continuation of application No. 29/730,562, filed on Apr. 6, 2020, now Pat. No. Des. 900,911, which is a continuation of application No. 29/711,372, filed on Oct. 30, 2019, now Pat. No. Des. 880,561, which is a continuation of application No. 29/699,947, filed on Jul. 30, 2019, now Pat. No. Des. 868,874, which is a continuation of application No. 29/665,724, filed on Oct. 5, 2018, now Pat. No. Des. 861,765, which is a continuation of application No. 29/549,344, filed on Dec. 21, 2015, now Pat. No. Des. 830,446, which is

(57) **CLAIM**

The ornamental design for a camera as shown and described.

DESCRIPTION

FIG. 1 is a top, front, and right side perspective view of a camera showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the camera in which the design is embodied that form no part of the claimed design.

1 Claim, 7 Drawing Sheets

Related U.S. Application Data

a continuation-in-part of application No. 29/548,661, filed on Dec. 15, 2015, now abandoned.
